UNITED STATES PATENT OFFICE

FRED HIMMEL AND ISIDORE HIMMEL, OF NEW HAVEN, CONNECTICUT, ASSIGNORS TO THE HIMMEL BROTHERS COMPANY, OF NEW HAVEN, CONNECTICUT, A CORPORATION

STORE-FRONT CONSTRUCTION

Application filed April 2, 1931. Serial No. 527,209.

This invention relates to an improvement in store-front constructions, particularly with reference to coupling metal strips for supporting sheets of glass, and is an improvement on the construction shown and described in Patent No. 1,784,689, granted December 9, 1930, and is similar in some respects to the construction shown in an application filed by us April 2, 1931, Serial No. 527,210.

The object of this invention is to provide simple means, but sufficiently rigid to firmly hold a pane of glass in place, and the invention consists in the construction as hereininafter described and particularly recited in the claims.

In the accompanying drawings:

Fig. 1 is a plan view of a store-front construction embodying our invention, with the outer member detached;

Fig. 2 is a front view of the same;

Fig. 3 is an end view taken on the line 3—3 of Fig. 2;

Fig. 4 is a sectional view taken on the line 4—4 of Fig. 2;

Fig. 5 is a sectional view taken on the line 5—5 of Fig. 4;

Fig. 6 is a sectional view taken on the line 6—6 of Fig. 4;

Fig. 7 is a perspective view of the rocker detached;

Fig. 8 is a perspective view of the mounting-block detached; and

Fig. 9 is a perspective view of the operating-block detached.

In carrying out our invention, we employ a mounting-block 10 formed in its outer face with a shelf 11 and with perforated trunnions 12 which are formed by cutting through the body of the block so as to form a chamber 13. The block is also slotted transversely through the chamber 13 forming guide-ways 14.

Between the trunnions 12 a rocker 15 is pivoted, one end 16 extending upward into engagement with a lip 17 formed in the upper edge of the outer member 18, which may be of any approved design. The other end 19 of the rocker extends into the path of the end 20 of a screw 21, which below the end is

formed with a reduced neck 33, and which is mounted in the upwardly-extending portion 22 of the body which is vertically threaded for the reception of said screw.

The upper end of the screw is exposed through an opening 23 in the inner member 24, the bottom 25 of which overlaps the bottom 26 of the outer member, which may be formed with a stop 27 to limit the inward movement of the outer member. The end 20 couples the screw 21 with a vertically-movable operating-block 28 which is movable in the chamber 13 and is provided on opposite sides with lugs 29 to enter and be guided by the guide-ways 14. This block 28 has a forwardly-projecting lip 30 and a rearwardly-opening notch 34 for receiving the neck and end of the screw 21. The lip 30 extends over the lower part of the rocker.

These blocks are located at intervals in the inner member and the shelf 11 forms a support for a sheet of glass 31 which may rest upon a strip 32 of wood or other suitable material.

The sheet of glass being placed in position, the screw is turned outward so as to allow the outer end of the rocker to drop to an extent sufficient to be engaged by the lip 17 of the outer member. When thus engaged, the screw will be turned inward carrying the block 28 downward and turning the rocker so that its upper end moves the outer member against the glass, and as the rocker is turned down, the screw or lower portion of the block turns the rocker until the desired pressure is obtained.

If desired, the mounting-block 10 may be provided on one or both ends with perforated ears 35 extending outward from the lower edge through which screws 36 or other fastening-means may extend into the window-casing, so that by fastening the blocks, the strips will be held in position without other fastenings.

We thus provide not only supports for the sheets of glass, but also means conveniently operated for clamping the glass in position.

We claim:

1. A store-front construction comprising inner and outer members, a mounting-block

- located in the inner member and comprising trunnions, a shelf above said trunnions, a chamber and transverse guides and a vertical threaded-bore, a rocker pivoted to said trunnions, an outer member with which the upper end of the rocker engages, an operating-block guided for vertical movement in the mounting-block, and a screw connected with said operating-block and extending upward through the mounting-block and adapted to engage with and depress the inner end of the rocker, whereby the outer end will force the upper end of the outer member inward.
2. A store-front construction comprising inner and outer members, a mounting-block located in the inner member and comprising a shelf, trunnions below the shelf, a chamber and transverse guides, a rocker mounted between said trunnions and formed with the forward end extending into engagement with the outer member, the other end extending into said chamber, an operating-block mounted in said chamber and guided for vertical movement therein, and a screw coupled with said operating-block and extending upward through the mounting-block, whereby the operating-block may be moved up or down to clamp or release the outer member.
3. A store-front construction comprising inner and outer members, a mounting-block located in the inner member, said block comprising trunnions, a shelf above said trunnions, the block also formed with a chamber and transverse guide-ways, an operating-block mounted in said chamber and provided with lugs entering the guide-ways, said block formed with a forwardly-projecting lip and in its rear face with an inwardly-extending notch, a screw having a head and neck entering said notch for engagement with the operating-block, said screw extending upward through the mounting-block, and a rocker pivoted to the mounting-block and having one end extending upward into engagement with the outer member and the upper end extending into the path of the operating-block.

In testimony whereof, we have signed this
specification.

FRED HIMMEL.
ISIDORE HIMMEL.
